CLAIM

The ornamental design for a vertical bifold cell phone wallet, as shown and described.

DESCRIPTION

FIG. 1 is a perspective view of a vertical bifold cell phone wallet with an exterior slot pocket and interior slot pockets according to one embodiment;

FIG. 2 is front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a perspective view of the vertical bifold cell phone wallet with an exterior slot pocket and interior slot pockets in an open condition;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The present application is directed to the design illustrated in the drawings. Portions shown in broken lines form no part of the claimed design.
